SWING

Roger K. Ericson, 906 W. Miner St.,
Arlington Heights, Ill. 60005

Filed June 12, 1968, Ser. No. 12,307

Term of patent 7 years

Int. Cl. D21—03

U.S. Cl. D34—5

FIGURE 1 is a top plan view of the swing showing my new design.

FIGURE 2 is a side elevational view.

FIGURE 3 is an end elevational view.

FIGURE 4 is a fragmentary perspective view of the top portion of the swing.

I claim:

The original design for a swing, as shown.
